Inventor

George W. Cook

UNITED STATES PATENT OFFICE.

GEORGE W. COOK, OF CHICAGO, ILLINOIS.

WINDOW AND DOOR AWNING OR SHADE.

SPECIFICATION forming part of Letters Patent No. 315,250, dated April 7, 1885.

Application filed July 17, 1884. (No model.)

To all whom it may concern:

Be it known that I, GEORGE W. COOK, a citizen of the United States, residing at Chicago, in the county of Cook and State of Illinois, have invented a new and useful Improvement in Window and Door Awnings, of which the following, in connection with the accompanying drawings, is a specification.

The nature of this invention consists in an adjustable folding metallic window or door shade.

The object of the invention is, first, the great durability of such a construction over that of the present canvas awnings; second, the better protection from the sun's rays, as the light and heat cannot penetrate the material used in the construction; third, it is not liable to take fire from flying sparks or from the burning of an adjacent or opposite building, but on the contrary can be used as a protection in these latter cases, while the canvas awnings increase the danger to the buildings to which they are attached; fourth, it is not necessary to remove this shade in the fall, it can remain a permanent fixture and be used to protect the window from rain, hail, and snow; fifth, as it will not retain or hold water, it does not require any attention during the time of or after a rain; sixth, in addition to its usefulness it can be made very ornamental to buildings where inside blinds are used.

Figure 1 is a perspective view of the entire device as attached to a building and lowered to the full extent; Fig. 2, a front view with the several sections, A, elevated or closed up; Fig. 3, a view from the rear, showing cords, pulleys, and points of attachment with sections A lowered; Fig. 4, sectional view through the center, one-half of the sections elevated, remainder shown in dotted lines; Fig. 5, detail view of one of the sections A; Fig. 6, section on line 6 6 of Fig. 5; Fig. 7, section on line 7 7 of Fig. 4.

Like letters of reference indicate like parts. I construct the series of leaves, consisting of the top and sides, A A and A', (shown in Figs. 1 and 5,) out of tin, sheet-iron, or any other metallic substance, commencing with the leaf A' and decreasing the size of each leaf in succession, so that they will fold one inside of

the other, and in order to strengthen and hold the metal plates in position I fold in each edge of the several leaves a wire or iron rod, as shown at a⁴ in Figs. 4 and 6. This rod is so folded and inclosed in the edges of each leaf 55 or plate as to form a projection the thickness of the rod alternately on the two sides and top of each leaf, (shown in Figs. 4 and 4,) so that when the leaves are open or extended, as in Fig. 1, these projections lap each other at 60 the top, and form a lock against a separation of the leaves when the awning is in use. The outer leaf, A', is permanently attached to the window or door casing, or to the main building, as herein represented, by means of bolts 65 or screws passing through the flange B. This section of the leaves serves as a receptacle for the balance when they are drawn up to their full extent, as in Fig. 2. The leaves are all attached together and hinged by means of the 70 bolts a⁵ passing through them; and as the weight of all of the leaves, except A', rests upon the two bolts, I attach the brackets C to the window-casing or other suitable points, by which one end of the bolt is supported, the 75 other end having a bearing upon the fixed section A'.

As the device will require painting, in order to prevent the flat surface of the leaves from rubbing against each other, and thereby disfigure the sides, I place the washers a⁶ between each leaf at the bottom or tapered ends, and upon the sides, at or near the top of each section, I place the bars a², which in raising and lowering the sections have a friction-bearing 85 8c against the side projections, a⁴, of the next leaf.

In order to raise each section or leaf in turn, commencing at the bottom or lower section, I place the flange a on each of the two lower 9c corners of this section. (Better shown in Fig. 2.) This flange projects sufficient to receive the edges and weight of all the other adjustable sections. Upon the inside of the lower section I place the slugs a' a', to which I attach 95 one end of each of the cords D D, and passing the cords over the pulleys d d, which are placed at the top and back corners of the shade or upon the window-casings, as shown in Figs. 3 and 4, I hereby have the means for operat- 100

ing the device. As the metal used for the foundation of this construction will of necessity require to be light, and may require strengthening or stiffening (in addition to the 5 rods a^4) in the construction of the larger sizes, I would recommend a lining of thin board on the insides of the sides and top of each leaf or section.

In the construction of the shade I do not 10 confine myself to any particular number of the folding leaves, nor to the shape of that part of the leaf forming the top, as they will of necessity be shaped at the top to conform with the top of the windows and doors, many 15 of which are oval and half-round.

What I claim, and desire to secure by Letters Patent, is—

1. In awnings consisting of a series of connected side and top slats forming frames arranged to slide one within the other, as herein 20 shown, the combination of the incased strengthening and lock rods a^4 , applied to the edges and projecting alternately in opposite directions from the two sides of each slat, substantially as set forth.

2. The combination, in an awning consisting of a series of folding frames, as set forth, of the friction-bars a^2 with the inside rods, a^4 , of each slat.

GEORGE W. COOK.
